DISPENSER FOR COLLAPSIBLE TUBES

Joseph H. Blake, Seattle, Wash.

Application November 7, 1938, Serial No. 239,361

3 Claims. (Cl. 221—60)

My present invention relates to the art of dispensing equipment for collapsible tubes and more particularly to a quantity indicating dispenser for collapsible tubes.

5 My present device has certain features, in common with tube dispensers, that are intended to provide a fixed positioning of collapsible tubes and permit of their convenient use. Further, my invention contemplates the graduation of the collapsible tube in such a manner that materials in the tube may be dispensed in known quantities.

10 It will be apparent, it is believed, that my dispensing device may be used with tubes such as are normally used for toothpaste, shaving cream and the like, but it is contemplated that it will have a broader or more general application. There are many commodities that are now sold in collapsible tubes. This use is gradually increasing and it is the purpose of my present invention to provide a means that will make it possible to measure, with reasonable accuracy, such items as shortening and food products of various kinds, that a housewife may choose to measure in definite quantities as a convenience in making a recipe.

15 Another important object of my present invention is to provide a dispenser for tube cream which will accommodate a wide variety of tube sizes.

20 A further object of my invention is to provide a device which will seal the tube after cream has been dispensed therefrom.

25 Still another object is to provide a device of this character which will easily accomplish the purpose intended and which will yet be economical to manufacture, sightly in appearance and sanitary. In my present invention it is believed that I have achieved a desirable solution of this problem.

30 Other and more specific objects will be apparent from the following description taken in connection with the accompanying drawings, wherein

35 Figure 1 is a perspective view showing one desirable form of my dispensing means.

40 Figure 2 is a perspective view showing the pressure roll and winding key assembly.

45 Figure 3 is a front elevation of my dispensing device with a tube in place and showing the same as dispensing paste upon a tooth brush.

50 Figure 4 is a side elevation, in section, taken through the longitudinal center line of Figure 3, but showing the closure member in place sealing the tube.

Figure 5 is a cross-sectional view taken along the line 5—5 of Figure 3.

55 Figure 6 is a fragmentary, front elevational view, partly in section, showing the closure member in its depressed position, but with certain other parts removed to more clearly illustrate its construction.

60 Figure 7 is a perspective view, bracketed, partly in section, and showing the dispensing end of a collapsible tube; in this showing a modified form 10 of structure is employed.

Figure 8 is a fragmentary, front elevation, partly in section, showing the dispensing tube in position.

65 Figure 9 is a cross-sectional view taken along 15 the line 9—9 of Figure 8.

70 Figure 10 is a perspective view showing my tube dispensing equipment with a modified form of closure member.

75 Figure 11 is a perspective view showing a collapsible tube having a tip particularly suited for this type of dispenser.

80 Figure 12 is a perspective view showing the lower side of my closure device.

85 Figure 13 is a perspective view showing the form of opening employed in the lower bracket of my tube support.

90 Figure 14 illustrates, in perspective view, the upper side of the closure member illustrated in Figure 12.

95 Figure 15 is a side elevation, in section, taken through the tube dispensing end and closure member.

100 Figure 16 is a front elevation, in fragmentary form and partly in section, showing my closure member as applied to a threaded tube.

105 Figure 17 is a perspective view, bracketed, showing a further modification of the tube closure member and method of securing the collapsible tube tip in place.

110 Referring to the drawings, throughout which like reference characters indicate like parts, 10 designates the base or backing member of my dispenser. This should be of a size to conform to the size of tube with which the device is to be 115 used and is normally provided with means for securing the same in place as, for instance, the bayonet type screw holes 11 and 12.

120 Formed as part of body 10 are the flange guideways 14 and 15. These guideways are formed as 125 angles so that the guideways proper are outstanding from the base portion 10 which lies flat against the supporting wall. This provides freedom of movement for frame 16 which carries the tube compressing means. At the bottom of base 130

10 is a shelf member 18 which is formed, preferably, integrally with base 10 and, due to the bracing effect of the guideways 14 and 15 provides unusual rigidity even though made of fairly light 5 gauge metal or molded material. It will be understood, it is believed, that any suitable material may be used to form the base and certain other parts of my device. Stamped metal appears to be the most durable of known materials although 10 molded plastics will serve very effectively and can be produced in a finished form probably cheaper than any form of metal that needs later to be finished.

The tube collapsing member 16 is formed as a 15 U-shape member having a straight front portion 20 and curved-in parallel ends 22 and 23. These ends are provided with guide members to engage the front and rear sides and the edge of guideways 14 and 15. These guides consist of a front 20 guide as 24, and rear guides 26 and 27. The rear guides are set back from the plane of guide 24 so as to provide space for guideways 14 or 15. The hooked members 26 and 27 also provide a bearing on the edges of guideways 14 and 15 25 and in this manner, due to the relatively wide spacing of members 26 and 27, frame 16 is held in a firm rigid position, yet disposed to be slidable the length of the guideways.

Each of the inturned ends 22 and 23 are provided with slots 28 and 30. These slots are 30 adapted to receive the winding key 32 and the presser roller 34. It will be noted that the body portion of key 32 is enlarged to provide sufficient material for slot 35 and the two ends are of 35 smaller diameter so that they may be slipped through slots 28 and 30 before frame 16 is placed on guideways 14 and 15. In a like manner the presser roller 34 is provided with an enlarged body diameter with reduced end portions to engage in 40 slots 28 and 30 and the same is put in place at the same time, normally, that the winding key is installed. To provide inward pressure at all times on roller 34 I have secured a leaf spring 37 to frame 16, as by the rivet at 38. The ends of 45 spring 37 are notched so as to partly encircle roller 34 and in this manner provide inward pressure on the same. It will be apparent that as the amount of material wound up on key 32 increases, the roller 34 is forced back against spring 50 37 which with the present construction can be deflected owing to the fact that the ends of spring 37 can slide outwardly on roller 34.

The parts thus far described are all common to the various forms of my device illustrated in 55 the accompanying drawings. Due to the fact, however, that there are many different conditions under which tubes are used it has been found desirable to provide different types of cap arrangements on the tubes and these necessitate 60 modification of the lower anchoring means. In Figures 1, 3, 4, and 5 I have provided that there will be pivotally secured to the rigid shelf 18, a clamp member 40, disposed to swing in a horizontal plane, which is urged by spring 42 into its 65 closed position in which notch 43 is brought to engage the neck of a collapsible tube when in position. In this form it has been found desirable to provide a notched centering means at 45 and this notch in coaction with the pivoted member 70 40, which in turn is provided with a knife-edged bearing on the notch portion 43, will secure in position a wide range of sizes of the ordinary screwed on cap type of collapsible tube. Disposed below shelf 18 is the pivoted closure member 47. 75 This member is provided with a torsion spring as

48 which tends at all times to force closure member 47 up into a horizontal position normally abutting shelf 18 except when a tube is in place at which time it engages the end of the tube neck and thus provides a closure or cover therefor. 5

This has been found to be a convenient means of closing the tube after the cap has been removed in that for many types of use as for instance in dispensing toothpaste, the toothbrush as B may be employed as illustrated in Figure 3 10 and by merely pressing down on closure 47 with the brush and then turning key 32, a quantity of cream as indicated at C can be easily collected on the brush. When this is done the brush is merely removed and spring 48 raises closure 47 so 15 as to close the tube opening.

In Figures 7, 8, and 9 a modified form of tube securing means is employed in which shelf 18 is provided with a downward directed extension 50. This tubular extension is provided with an 20 opening 52 at one point so that the pivoted securing lever 54 may pass partly through member 50 and engage a notch 56 formed in the neck of tube 57. The closure member as 47 might be employed although I have in this instance shown a horizontally pivoted closure member 59 which is 25 pivoted at 60 and swings in the plane of shelf 18 so that a cutting, shearing, or wiping action is applied by the closure member.

In Figures 10, 11, 12, 13, and 14, I have illustrated a further modification of the tube dispensing neck and the closure for the same. In this instance tube 62 is provided with either a threaded or notched end and has two lugs as 64 and 65 that assure accurate positioning of the 35 tube so that the graduation 67, formed on the tube to indicate quantities of material, will always be properly positioned for easy and accurate reading. This form of tube requires a slight modification of shelf 18 in that in addition to the round 40 opening 68 extensions of this opening as 69 and 70 are required so as to position lugs 64 and 65. These lugs normally are off center, as far as opening 68 is concerned, so that tube 62 can only be placed in this opening in shelf 18 in one 45 position so that the graduations 67 will always face outwardly.

The closure member illustrated with this form is in effect a rotary valve which is either secured to the threaded portion of the tube or secured to 50 a threaded downward extension 72 of shelf 18. The closure is provided with a body portion 74 and the rotating plug 76. This plug is held in place by screw 77 and is turned by means of the knurled portion 79. It will be apparent, it is believed, that the tube is in its dispensing position when the through opening 80 is in alignment with the axis of the tube neck and when this member is turned so as to place this opening out of alignment the tube is sealed against any accidental 60 disbursement or against hardening of the contained paste due to contact with the air. 65

In Figure 17 the construction is slightly modified in that the closure member while remaining the same is threaded to the downwardly extending member 72 of bracket 18 and a tube similar to the one shown in Figures 7, 8, and 9, is seated in the opening 82 of shelf 18 and locked in that position by means of the pivoted lever 84. This may be knife-edged as is illustrated for the swing- 70 ing lever 40 at 43 or it may engage in an annular groove formed in the tube neck as shown at 86. 75

Method of operation

My present device contemplates the eventual 75 more general use of collapsible tubes which need

not necessarily be made of metal, but of various materials, such as Cellophane or other synthetic products to more readily adapt the collapsible tube to the dispensing of shortening and other materials, particularly food products; and, to take full advantage of such possibilities, I prefer that the tube 62 be graduated as is illustrated at 67 in particularly Figures 3 and 11 so that definite amounts, as tablespoonfuls, or portions of cupfuls, 10 or ounces, may be accurately dispensed by turning key 32 until the proper graduation is in alignment with bar 20 and roller 34. It will be noted, particularly in Figure 4, that by sighting over bar 20 and presser roller 34, accurate reading may be 15 obtained.

The foregoing description and the accompanying drawings are believed to clearly disclose a preferred embodiment of my invention but it will be understood that this disclosure is merely illustrative and that such changes in the invention may be made as are fairly within the scope and spirit of the following claims.

I claim:

1. The combination with an upright support 25 and means thereon for supporting and winding the body of a collapsible tube, of a notched-shelf rigid with the support and forming a rigid jaw for the nozzle of the tube, a jaw pivoted on the upper face of the shelf and having a recess co- 30 acting with the notched-shelf to clamp the nozzle, a spring mounted on the upper face of the rigid jaw, an off-set lug on the pivoted jaw engaged by the free end of the spring to provide a snap action to the jaw in swinging to and from closed

position, and a spring actuated closure pivoted to the shelf at the rear of the rigid jaw and adapted to be swung downwardly by pressure from a brush.

2. In a dispensing device, the combination with 5 a support having spaced guide flanges, means mounted on the support for retaining the nozzle end of a collapsible tube, and means for closing the nozzle of the tube, of a roller frame having rearwardly extending slotted side arms, guide 10 means at the end of each arm for co-action with said guide flanges, a pair of clamping rollers journaled in the slotted side arms, one of which rollers forms an anchorage for the collapsible end of the tube, means for rotating the other roller, and resilient means mounted in the frame for urging 15 the operating roller in frictional contact with the tube.

3. In a dispensing device, the combination with 20 a support having off-set lateral guide flanges, means mounted on the support for retaining the nozzle end of a collapsible tube, automatic means for closing the nozzle of the tube, of a slidable roller-frame having rearwardly extending slotted arms, said arms having guide lugs engaging the 25 flanges, a pair of clamping rollers journaled in the slotted arms, one of said rollers having a longitudinal slot to receive the collapsible end of the tube, a bow-spring mounted within the front 30 of the frame with its ends engaging the other roller to cause frictional engagement of the last mentioned roller with the collapsible tube, and means for turning the slotted roller.

JOSEPH H. BLAKE.
